UNITED STATES PATENT OFFICE.

CHARLES E. WAXBOM, OF COLUMBUS, OHIO, ASSIGNOR TO THE JEFFREY MANUFACTURING COMPANY, OF COLUMBUS, OHIO, A CORPORATION OF OHIO.

COAL-MINING MACHINE.

Application filed December 27, 1923. Serial No. 683,001.

The present invention relates to certain new and useful improvements in coal mining machines, and especially to that class of mining machines in which each is provided with track wheels adapted to travel over the tracks of the mine and is adapted to perform its cutting operations while supported on said track wheels.

The especial object of this invention is to provide a machine of the class described having improved power connections between the motor and the track wheels whereby the machine is adapted to be propelled along the tracks of the mine while the cutting element is in any of its various positions of adjustment.

In the accompanying drawings I have illustrated a machine embodying my invention, but it is to be borne in mind that I do not limit myself to the construction here shown, as there are many modifications which may be made without departing from the spirit of my invention.

Of the drawings

Figure 1 is a side elevation of a machine embodying my invention.

Fig. 2 is a general plan view of the machine illustrated in Fig. 1.

Fig. 3 is a fragmentary sectional view taken along the line 3—3 of Fig. 2.

Fig. 4 is a sectional view along the line 4—4 of Fig. 2.

Fig. 5 is a sectional view along the line 5—5 of Fig. 2.

Fig. 6 is a plan view of the machine with the upper parts broken away to disclose the wheels and axles.

Like numerals refer to similar parts in the several figures.

This machine is mounted upon a truck frame 1 having journal bearings 2 in which are journaled the axles 3 and 4, and to the axles are fixed the track wheels 5 adapted to travel over the rails 6 of the mine tracks.

At the rear of the truck I preferably provide a step 7, and a cable reel 8, which may be of any preferred construction, is usually provided upon which may be wound the electric conductor cable 9, through which the power is supplied to actuate the machine.

Securely attached to the truck platform, arranged in an equilateral triangle, are three upstanding studs 10 upon the surface of which are formed screw threads. Each of

these studs is fitted with two nuts 11 which have beveled surfaces, and are provided with radial apertures 12 adapted to engage the end of a bar, or spanner wrench, by which they may be turned.

13 represents an annular ring of preferably rectangular cross section. Equally spaced about this ring are three depending brackets 14, each comprising two parallel side bars 15 at the lower end of which are formed a horizontal yoke 16 having an aperture adapted to receive one of the studs 10. The nuts 11 are positioned one above the other below the horizontal yoke on each of the studs and the apertures in the yokes are large enough to admit of a certain amount of lateral movement of the yokes relative to the studs. It will be seen that by proper adjustment of the nuts 11 the brackets 14 with the ring 13 may be raised and lowered to adjust it to any desired elevation relative to the truck, and may be locked in such position by the tightening of the upper nuts against the yoke.

The operative parts of the machine are mounted upon a main frame casting 17 which rests directly upon the top of the ring 13 and is adapted to rotate relatively thereto. A series of rollers 18 rotatably mounted upon the underside of this frame casting 17 and adapted to engage the inner surface of the ring 13, serve to guide the frame casting in its rotation. A series of brackets or clips 19, attached to the underside of the frame casting 17, engage the under side of the ring 13 to prevent upward movement of the frame relative to the ring. A series of notches 20 formed on the edge of the frame casting are adapted to be engaged by the latch 21 which is slidable in the bearing casting 22 attached to the ring 13, to hold the frame in any desired angular position. When the latch 21 is in its lower position it is disengaged from the notches 20 and the frame, with its attached mechanism, is free to turn upon the ring. Means for holding the latch in either its upper or lower position is provided in the pin 23 adapted to be inserted in the holes 24 and 25 of the bearing casting 22.

Supported from the under side of the frame casting 17 is an electric motor 26 the armature shaft 27 of which is provided with a spur pinion 28 in mesh with the spur gear 29. This spur gear is attached to a sleeve

30 keyed to the driving shaft 31 and rotatably supported in the journal bearing 32 formed on the frame casting 17. At the inner end of the sleeve 30 is formed a flange 33 having apertures 34 through which extend the pins 35 of a pin clutch member 36 which is slidable upon the surface of the sleeve 30. A second sleeve 37 is rotatably mounted upon the shaft 31 and on the end 10 of this sleeve adjacent the flange 33 is formed a similar flange 38^a having notches adapted to engage the pin 35 of the clutch to drive the sleeve 37. Formed on the sleeve 37 is a worm 38 by which power is transmitted 15 to the track wheels to propel the truck as will be hereinafter set forth.

Rotatable upon the shaft 31 is a bevel gear 39 having an elongated hub 40 on the surface of which is formed a journal rotatably supported in a journal bearing 41 formed on the frame casting. Formed on the outer end of the hub 40 is a jaw clutch member 42 adapted to engage with a similar jaw clutch member 43 slidable upon the feather key 44 of the shaft 31. By this clutch arrangement the bevel gear 39 may be operatively connected with the shaft 31 and through the gear 29 with the motor 26. A thrust collar 45 is provided to prevent the clutch member 43 from sliding off the end of the shaft 31. Suitable ball bearings 46 are interposed between the sleeves 30, 37 and 40 to take the thrust of the worm 38.

The bevel gear 39 engages with a complementary gear 47 attached to the lower end of a vertical shaft 48 journaled in a suitable bearing 49 of the frame casting 17. At the upper end of the shaft 48 is fixed a sprocket wheel 50 by which is driven the chain 51 of the cutting mechanism. This cutting mechanism, is of the type commonly used with mining machines of this class, and comprises a chain supporting and guiding arm 52, extending horizontally from the frame casting 17, about the edges of which travels the cutter chain 51 to which are fixed the cutter bits 53. In the operation of such a mining machine the coal is cut by the moving bits 53 being forced against the coal by a horizontal movement of the cutter arm 52. This movement of the cutter arm is effected either by the rotation of the frame casting upon the ring 13, or by the bodily movement of the machine upon the track wheels. 55 Either of these movements may be accomplished by a feeding mechanism comprising a rope 54 adapted to be fastened at one end to a suitable abutment, and to be wound upon a cable winding drum 55 mounted upon the frame casting 17.

The drum 55 is rotatable upon a vertical shaft 56, journaled in a bearing 57 of the frame casting 17, to which it may be connected by a multiple disk friction clutch, the disks 58 of which are compressible by

the hand wheel 59 screw threaded to the extension 60 of the shaft 56. To the lower end of the shaft 56 is fixed a worm gear 61 which is engaged by a worm 62 mounted upon a horizontal shaft 63 supported in suitable bearings of the frame casting 17. To this shaft 63 is fixed a ratchet wheel 64 at either side of which are rotatively mounted two ratchet levers 65 between which extends the pivot pin 66. The pin 66 carries a pawl 67 adapted to engage with the teeth of the ratchet wheel 64. These ratchet levers are connected by the rod 68 with the straps 69 of the eccentric 70 fixed to and revolving with the bevel gear 47. By the rotation of this eccentric the ratchet lever 65 is caused to oscillate, and, by the engagement of the pawl with the ratchet wheel, the worm shaft is rotated to cause the rotation of the feed drum to wind the rope 54.

Rotatable about the ratchet wheel 64 is a shield 71, movable by the adjusting screw 72, and adapted to engage the pawl 67 to lift it from engagement with the teeth of the ratchet wheel. By the adjustment of the position of this shield the number of teeth over which the pawl passes at each oscillation of the ratchet lever may be controlled to vary the rate of winding the rope 54, and the consequent rate of feeding the cutter into the coal. Mounted upon the frame casting 17 are a plurality of guide sheaves 73 adapted to guide the feed rope 54 from the feed drum 55 to be led off from the machine in any desired direction.

When it is desired to rotate the cutting element to cut the coal, the rope 54 will be drawn out from the drum 55, passed around the guide sheaves 73 and its end attached to one of the lugs 74 projecting from the bracket 14. The hand wheel 59 will then be manipulated to cause the winding of the rope, and the adjusting screw 72 adjusted to regulate the rate of winding. When now the motor is actuated the cutters will be fed into the coal to cut it.

If it is desired to move the machine bodily along the track, to force the cutting mechanism into the coal, in what is termed the sumping cut, an anchor may be fixed in the coal face to which the ropes 54 may be attached, and upon winding the rope the machine will be drawn toward the anchor. The rate at which the rope is wound, even at the highest rate attainable with the ratchet drive above described, while suitable for feeding the cutters into the coal, is entirely too slow for the movement of the machine from one working place to another. It is therefore necessary to provide other means for propelling the truck along the tracks of the mine from place to place.

For this purpose I have provided the worm 38, above described, which is in engagement with a worm gear 75 fixed to the

- upper end of a vertical shaft 76 supported for rotation in a journal bearing 77, of the frame casting 17, which is exactly concentric with the ring 13. The lower portion 78 of the shaft 77 is square and is slideable in a sleeve 79 journaled in a journal bearing 80 attached to the truck platform 1, to drive said sleeve, forming a telescoping drive connection between the turntable and the truck.
- 5 To the lower end of the sleeve 79 is fixed a bevel gear 81 engaging with a complementary gear 82 attached to a transverse shaft 83 supported in bearings 84 of the truck frame. A sprocket wheel 85 fixed to the 15 shaft 83 transmits power to the axle 3 through the chain 86 and the sprocket wheel 87, and the two axles are connected together by the chain 88 and sprocket wheels 89 and 90.
- 20 The machine above described is particularly adapted to cut a kerf in the mine wall in the plane of a band of impurities, and thereby prevent the mixing of the impure coal with the material loaded for shipment 25 from the mine, as such dirty bands are commonly more or less inclined from the general level of the vein, the adjusting nuts 11 on the different studs 10 must be adjusted to different heights to cause the inclination 30 of the supporting ring 14 to correspond with the inclination of the plane of the impure band so that the cutter arm 52 may follow that band and remove it. If the shaft 76 were made rigid from end to end, such inclined adjustment would cause it to bind in the bearings 77 and 80 and thereby prevent its satisfactory operation. If the inclination were considerable the shaft 76 would be bent or the bearings 77 and 80 broken.
- 35 To permit such angular adjustment of the cutting mechanism I have provided in the shaft 76 a flexible coupling 91, of the type known in the art as a universal joint, which is positioned in the transverse plane of the 40 yokes 16, and consequently, is concentric with the supporting ring 13 and the truck bearing 80. By virtue of the flexibility of the driving connection thus provided, the truck wheels may be actuated from the 45 motor 26 when the cutting mechanism is in any position of vertical adjustment, regardless of its angular relation to the longitudinal lines or transverse planes of the mine track.
- 50 What I claim is:—
1. In a machine of the class described, the combination with a wheel supported track guided truck, of a horizontally rotatable turntable positioned above said truck and adapted to vertical adjustment relative 55 thereto, cutting mechanism projecting laterally from said turntable and adapted to engage the mine wall to cut a kerf therein, a motor mounted upon said turntable and arranged to actuate said cutting mechanism, and means operable when said turntable is in any position of vertical adjustment and regardless of the angular relation of the cutting mechanism to the longitudinal lines or transverse plane of said track to connect the motor upon the turntable with the truck wheels to propel the machine along the mine track.
2. In a machine of the class described, the combination with a wheel supported track guided truck, of a horizontally rotatable turntable positioned above said truck and adapted to vertical adjustment relative thereto, cutting mechanism projecting laterally from said turntable and adapted to engage the mine wall to cut a kerf therein, a motor mounted upon said turntable arranged to actuate said cutting mechanism, a vertical telescoping shaft concentric with said turntable to transmit power from the motor upon the turntable to the truck wheels to propel the machine along the mine track, and a universal joint arranged in said vertical shaft to permit the adjustment of said turntable to planes inclined to the transverse planes of said mine track.
3. In a machine of the class described, the combination of a truck, truck driving means, a horizontally rotatable turntable, vertically adjustable connections between said turntable and said truck, cutting mechanism projecting from said turntable and adapted to engage a mine wall, a motor to drive said cutting mechanism, a vertical shaft connecting said motor with said truck driving means, and a universal joint in said shaft to permit the adjustment of said turntable to planes inclined to the horizontal.
4. In a machine of the class described, the combination of a truck, truck driving means, a horizontally rotatable turntable, a plurality of vertically adjustable connections between said turntable and said truck, cutting mechanism projecting from said turntable and adapted to engage a mine wall, a motor mounted on said turntable to drive said cutting mechanism, a vertical telescoping shaft connecting said motor and said truck driving means, and a universal joint in said vertical shaft to permit adjustment of said turntable to planes inclined to the horizontal.
5. In testimony whereof I have hereunto set my hand.

CHARLES E. WAXBOM.
